FIG. 5

H. G. G.

6. H. Evers.

Dr. John A. Bomhardt

HTTIV.

UNITED STATES PATENT OFFICE.

CHARLES H. EVERE, OF CLEVELAND, OHIO.

SMOKEHOUSE.

Application filed May 3, 1920. Serial No. 378,526.

To all whom it may concern:

Be it known that I, CHARLES H. EVERE, a citizen of the United States, residing at Cleveland, in the county of Cuyahoga and State of Ohio, have invented certain new and useful Improvements in Smokehouses, of which the following is a specification.

This invention relates to gearing for the conveyors of smoke-houses and has for its object to provide an improved means for operating and controlling the endless chains carried within the smoke-house and which support the sausage or the like which is to be smoked, such as is fully described in the patent granted to myself and C. R. Hildebrandt and bearing #712,662, and date of November 4, 1902.

The invention further consists in the provision of means whereby said chains may be driven by power or manually.

The invention further consists in the certain construction and combination of parts hereinafter described, illustrated and particularly pointed out in the appended description and claims.

Referring to the drawing wherein like reference numerals indicate similar parts of reference throughout the various views, Fig. 1 is a sectional side elevation of a smoke-house constructed in the usual manner and having the improved driving mechanism embodied thereon; Fig. 2 is a front elevation; Figs. 3 and 4 are detail views of the main bearing and its drive; Fig. 5 is an enlarged detail showing the manner in which the driving gears are separated to permit of manual labor being employed and Fig. 6 is a detail view on the line 6-6 of Fig. 2.

The smoke-house 1 in general consists of a relatively high structure built of masonry or the like. In the lower part thereof are located the fire places 2-2 and beneath these the customary ash-pits 3. Part way up this structure are openings 4 by means of which the articles to be smoked are taken in and out of the smoke-house and from the top of the house projects a chimney 60.

The hoisting apparatus comprises two pairs of sprocket wheels 5 and 6 which are mounted upon shafts 7 and 8 journaled at the top and bottom of the structure 1, endless chains 9 and a plurality of carriers 11. The wheels 6 are mounted in close proximity over the fire places, while the wheels 5 are as far distant therefrom as space will per-

mit, preferably near the top of the structure and directly beneath the chimney. Some of the chain links 10 are of special formation thereby to support the carriers 11. The particular manner in which the foregoing is constructed has been fully described in the patent above cited and as any suitable construction may be employed further description is deemed unnecessary.

Referring to the figures it will be seen that the aforementioned shaft 7 projects through the structure and is supported in suitable bearings 12 carried by the walls thereof. At one end and outside of the wall said shaft 70 has fixed thereto a worm wheel 13 which meshes with a worm 14 keyed upon a transverse shaft 15 lying parallel to and outside of the structure. This shaft is mounted in specially designed bearings indicated generally at 16 and 17 which will be herein-after described and which permit of adjustment of the shaft 15. This shaft has secured at one end a sprocket wheel 18 and a worm wheel 19 and said worm wheel meshes with a worm 20 splined upon the shaft 21 of a motor 22, the motor being supported upon a shelf 23 secured to the structure, and the end of the shaft 21 upon the end of which the worm 20 is secured, being supported in a bearing member 24. Electrical energy being introduced into the motor it will be apparent that motion is transmitted to the shaft 7 at a greatly reduced speed, thereby procuring a very slow movement of the carriers, and by means of which satisfactory curing of the meats is obtained during the completion of but one circuit of said carriers.

It is at times essential that the position of the carriers be adjusted very carefully especially when loading or making repairs, and for this purpose I provide a means for manually operating said carriers. This consists of a hand crank 25 mounted in a bracket 26 carried by the structure and in a position which will be convenient for the operator to reach, and said crank has secured thereto a sprocket wheel 27 which is geared to the aforementioned sprocket wheel 18 through a chain 28. Obviously it would be impossible to drive the shaft 15 were the worm wheel 19 to remain in mesh with the worm 20, and to overcome this I provide a split collar 29, provided with hinge members 30 and locking ears 31, which is placed upon the shaft 21 between the worm 20 and the bearing support 32 of the bearing 24. After

the removal of said collar, rotation of shaft 15 causes the worm 20 to move longitudinally of shaft 21 until such time as it is free of the worm wheel. This it is caused to do by 5 the pitch of the worm and the position it assumes at this time is clearly shown in Figure 5.

To permit of perfect aligning of the shaft 15 and to compensate for wear to the gearing thereon the aforementioned bearings 16 and 17 are provided with a vertical adjustment. This consists of a plate 35 fixed to the wall of the structure by means of bolts 36, said plate is provided at its bottom with 15 an outwardly projecting flange 37, through which projects set screws 38 provided with jam nuts 39. The pillow blocks or actual bearings 50 for said shaft are provided with a back flange 40 by means of which they are 20 secured to the plate 35 by bolts 41 passing through slots 42 in the flange 40, and the bottom edge of said flange rests upon and is further supported by the set screws 38. Now 25 by loosening the bolts 41 and manipulating the set screws 38 a vertical adjustment of the shaft may be obtained.

Referring particular to Figs. 1 and 2 it will be seen that the doors which close the openings 4, are provided with hand holes 30 45 closed by a swinging door 46 and in proximity to the door latch 47. By this means, were a workman to inadvertently remain within the structure with the door closed and after the fires were started he would be 35 able to release himself and prevent injury to himself from suffocation.

The above construction is capable of being modified in various ways, therefore I wish it to be understood that I do not care to be limited therein further than is required by 40 the state of the art or that which comes within the scope of the appended claims.

I claim:

1. The combination of a driven shaft having a worm gear thereon, a motor shaft 45 having a worm slidable thereon and engaging said gear, a bearing in which the motor shaft rotates, a removable collar on the motor shaft, between said bearing and the worm, and adapted when in place to hold said worm engaged with the gear, and when removed to permit sliding movement to disengage the worm from the gear, and means to manually operate the driven shaft when said collar is removed. 55

2. The combination of a driven shaft, a worm gear thereon, a motor shaft, a worm thereon engaging said gear, said worm being splined on the motor shaft for lengthwise movement, a removable device normally holding said worm against lengthwise movement and in driving engagement with said gear, and when removed permitting said worm to slide lengthwise out of engagement with said gear, and means to operate the 60 driven shaft by hand. 65

In testimony whereof, I do affix my signature in presence of two witnesses.

CHARLES H. EVERE
